UNITED STATES PATENT OFFICE.

ELSIE H. HORTON, OF MINNEAPOLIS, MINNESOTA.

TRANSLUCENT DECORATION.

Application filed November 27, 1922. Serial No. 603,581.

The object of this invention is to provide a structure consisting of a group of translucent structures imitating in form or shape various kinds of fruits, vegetables or other articles.

5 The object I have in view is to provide a grouping of such translucent structures upon a suitable frame or support which may be arranged in front of a source of light such as an electric lamp or a series thereof, whereby the 10 rays of light passing through the translucent structures will be diffused while the individual structures will each retain its own coloring imitating the natural object that it is intended to represent.

15 In the accompanying drawings:

Figure 1 is a perspective view showing a completed structure embodying my invention;

20 Figure 2 is a rear or underside view of the supporting frame work showing a preferable arrangement of incandescent electric lamps in connection therewith;

25 Figure 3 is an elevation and partial section of one of the individual translucent structures employed in making up the completed decoration;

Figure 4 is a view similar to Figure 2, but with the lamps omitted in order to show the central ring; and

30 Figure 5 is a vertical sectional view of the dome-frame.

In my Patent No. 1,479,920, June 10, 1924 I have illustrated, described and claimed an individual translucent structure, such as is 35 employed in the completed decoration, and I have also in said patent claimed the method or process of making such individual structure.

40 In the drawings, I provide a frame or base preferably in the form of an arched or spherical segment or dome. This dome consists preferably of a base ring 2, a smaller intermediate ring 3 and a polar ring 4. These rings are preferably of relatively stiff wire and are disposed in parallelism. A plurality of meridian members 5, similarly of wire, extend from the base ring 2, are secured intermediately to the ring 3, and are convergent toward the ring 4. These meridian members 45 are terminally secured, as by solder, to the base ring 2 and the polar ring 4 and also intermediately to the ring 3 thus providing a reinforced frame of dome-like configuration. Preferably, this dome frame is covered by a 50 translucent covering 6 such as is afforded by organdie, silk, or a similar fabric coated with

a gelatinous or similar substance to give the dome a hardened surface. A suitable lamp preferably an incandescent electric lamp 7, or a series thereof, will be located within the 60 domed supporting structure to which said lamps may be secured by any suitable means.

Each of the individual translucent structures is designated by the reference numerals 8. Each is provided preferably with a suitable stem 9 by means of which the same may be secured to the dome support, or a series of said wires may be secured together forming a group of any particular type of structures and such group may then be secured to 70 the dome support.

Each of the individual structures 8 is hollow and translucent and colored or tinted to imitate the particular natural object it is intended to represent. Each of said individual structures is preferably formed of a foundation comprising a sheet of fabric, pressed over a form to the desired shape and suitably tinted or painted or otherwise colored and kept in shape by form-retaining coatings of wax 80 and protected by a water-proof coating of shellac, varnish or similar material.

These hollow colored translucent structures are suitably grouped upon the dome-shaped retaining base or support and the spaces 85 between the same may desirably be covered or partially covered by artificial leaves imitating the foliage of the trees or plants upon which natural objects imitated by the structures are produced.

In using this decoration the electric lamp or lamps will be suitably arranged and secured within the domed supporting structure and the completed structure will be placed upon the wall or ceiling of the room or upon a table 95 or other desired support, and the rays of light from the lamps passing through the individual structures will be diffused each article retaining its own distinctive coloring. The diffusion will be aided also by the artificial 100 foliage arranged upon the support which foliage is also translucent.

The result of the diffusion of the light by the translucent colored objects will be a harmonious and pleasing representation and imitation of the various natural objects represented and reproduced by the several individual structures.

I do not limit myself to the details of the structure of the supporting base or to the particular form or grouping of the individual structures or to any specific natural objects 110

as models for said individual structure, as the same may be varied in many particulars without departing from my invention.

I claim as my invention:

- 5 The combination of a dome-shaped form to provide a recessed portion to receive a lamp, a translucent fabric covering for said form said covering being coated with a gelatinous substance which hardens on exposure to give
- 10 the covering a glazed surface, a series of translucent form retaining structures made up each

of an interior tinted fabric cover with a translucent coating shaped and colored to imitate fruit and vegetables said structures grouped upon said dome-shaped structure whereby 15 when said lamp is lighted, a combination of the colors upon the translucent fabric covering and the hollow structures will be brought out.

In witness whereof, I have hereunto set my 20 hand this 9th day of November, 1922.

ELSIE H. HORTON.
